CONVERSION OF HYDROCARBON OIL

Charles W. Hussey, Chicago, Ill., assignor to Universal Oil Products Company, Chicago, Ill., a corporation of Delaware

Application August 31, 1939, Serial No. 292,853

4 Claims. (Cl. 196—49)

The invention relates more specifically to an improved process involving thermal cracking and catalytic cracking of hydrocarbon oils in a co-operative and interdependent manner to simultaneously produce regulated amounts of commercial motor gasoline and aviation-base gasoline in a unified system of relatively simple form which possesses construction and operating advantages and a high degree of flexibility with respect to the relative proportions of the two types of gasolines produced.

The catalytic cracking step of the process herein provided is specifically directed to the type of reaction now known as "low temperature" catalytic cracking which, when employed to convert olefinic or olefin-containing hydrocarbon oil distillates, results in a product containing a high proportion of hydrocarbons of the paraffinic and aromatic series. As the name implies, low temperature catalytic cracking also differs from the usual type of catalytic cracking operation, which is normally conducted at temperatures of the order of 900° F. and higher, by the lower temperatures employed which may range, for example, from 500 to 850° F. under the usual operating pressures and, with the type of catalyst which I preferably employ, are usually of the order of 650 to 800° F.

No novelty is claimed herein for either the low temperature catalytic cracking step or the thermal cracking step per se and the invention resides in the novel and advantageous manner in which thermal and low temperature catalytic cracking are co-operatively combined. There is definite co-operative relation between the two steps in that cracking stock for low temperature catalytic cracking is derived from the thermal cracking stage of the system at a temperature suitable for conducting the desired catalytic cracking operation and, in the preferred embodiment of the invention, there is a further co-operative relation in that, after separating the desired relatively low end-point aviation-base gasoline from higher boiling conversion products of the low temperature catalytic cracking step, the latter are preferably supplied to the thermal cracking system at a point in the flow sequence therein beyond that from which the charging stock for the catalytic cracking step is removed, (such as, for example, the fractionator of the thermal cracking system) whereby catalytically cracked gasoline of higher end-boiling point than said aviation-base gasoline is commingled with the gasoline produced by thermal cracking to form the final motor gasoline product of the process and whereby

higher boiling fractions of the low temperature catalytically cracked products are included in the recycle stock subjected to thermal cracking.

One important advantage of the system herein provided resides in its adaptability to numerous existing thermal cracking systems, whereby the latter may be readily remodeled to provide a system in which both commercial motor gasoline and aviation-base gasoline may be produced in regulated amounts by the simple addition of a minimum of low temperature catalytic cracking equipment, employing as charging stock a regulated portion of the relatively clean vaporous conversion products formed in the thermal cracking system and derived from the latter at a point therein at which the temperature of the vapors is suitable for effecting their desired conversion in the presence of the catalyst. As applied, for example, to the well known "series chamber" or "full flashing" type of thermal cracking system of either the single coil or multiple coil variety, wherein hot conversion products from one or more cracking coils are passed through a high pressure reaction chamber maintained at cracking temperature, vaporous and liquid products being removed in commingled state from the reaction chamber and supplied to a reduced pressure vaporizing and separating chamber wherefrom relatively clean vaporous conversion products are supplied to fractionating equipment for the formation of reflux condensate and recovery from the vapors of materials boiling within the range of gasoline, the charging stock for the low temperature catalytic cracking step of the present process is preferably a portion of said relatively clean vapors removed from the reduced pressure vaporizing and separating chamber, the operating conditions in the latter zone being so controlled that the vapors may be supplied directly therefrom to the zone of catalytic reaction under temperature and pressure conditions desirable for conducting the low temperature catalytic cracking reaction.

The features of the invention are also readily applicable to many other specific forms of thermal cracking systems including those such as commonly employed for the reforming treatment of gasoline, naphtha and the like to improve its anti-knock value, wherein conversion products formed at high temperature and superatmospheric pressure in the reforming coil are cooled to a temperature at which detrimental further cracking will not occur and thence supplied directly to a vaporizing and separating chamber operated at substantially reduced superatmospheric pressure.

the charging stock for the low temperature catalytic cracking step likewise being derived, in such a system, from the reduced pressure vaporizing and separating chamber at the desired temperature and pressure level for conducting the low temperature catalytic operation.

The accompanying diagrammatic drawing illustrates one specific form of apparatus in which a combination thermal and catalytic cracking operation embodied by the invention may be conducted. The drawing is only illustrative, however, and it should be understood that the invention is not limited in its broader aspects to the specific operation described in conjunction with the description of the drawing.

Referring to the drawing, charging stock for the process, which may comprise any desired type of hydrocarbon oil ranging from crude petroleum or residual oil, such as topped or reduced crude, to light distillates, is supplied through line 1 and valve 2 to pump 3 by means of which it is fed through line 4 and may be directed, depending upon its characteristics, either through valve 5 in this line to the light oil cracking coil 6 or through line 7, valve 8 and line 9 to the heavy oil cracking coil 10 or through line 7, line 11 and valve 12 to fractionator 13.

Either the light oil cracking coil or the heavy oil cracking coil, or both, may be employed within the scope of the invention and when coil 10 is utilized the oil supplied thereto is heated to the desired cracking temperature during its passage therethrough, preferably at a substantial superatmospheric pressure. Heat for this cracking operation is derived from furnace 14 in which coil 10 is disposed. The heated conversion products from coil 10 are directed through line 15 and valve 16 into reaction chamber 17 which is optional equipment and is preferably employed when the oil to be cracked is of a relatively heavy nature or contains a substantial quantity of high-boiling components.

Chamber 17, when utilized, is preferably operated at a substantial superatmospheric pressure which may be substantially the same or somewhat lower than that employed in the communicating heating coil utilizing the lowest outlet pressure and, although not illustrated in the drawing, chamber 17 is preferably insulated to conserve heat and maintain an active cracking temperature in this zone.

In the particular case here illustrated, both vaporous and liquid conversion products are directed from the lower portion of chamber 17 through line 18, valve 19 and line 20 into vaporizing and separating chamber 21 which is preferably operated at a substantially reduced superatmospheric pressure relative to that employed in chamber 17.

When cracking coil 6 is utilized, the relatively light hydrocarbon oil supplied to this zone is heated, by means of heat supplied from furnace 22, to the desired cracking temperature and the resulting heated products discharged from this zone may be directed, all or in part, through line 23 and valve 24 into reaction chamber 17 or all or in part through line 25, valve 26 and line 20 into vaporizing and separating chamber 21, the pressure in the latter zone preferably being substantially lower than that employed at the outlet of coil 6.

Provision is made for introducing cooling oil through line 27 and valve 28 into the stream of conversion products being supplied to chamber 21 for the purpose of retarding or arresting fur-

ther cracking of these products and reducing the formation and deposition of coke or similar heavy carbonaceous materials. Any other suitable method and means of cooling, not illustrated, may be employed in conjunction with or substituted for the use of cooling oil in the manner illustrated. Separation of vapors from heavy residual conversion products is accomplished in chamber 21 and the conditions employed in the latter zone may be controlled to reduce the heavy residual conversion products to coke in this zone or to produce a liquid residue which is removed from the lower portion of the chamber through line 29 and valve 30 to cooling and storage or to 15 further treatment which may, when desired, involve, for example, further distillation to heavier residual liquid, coke or pitch-like residue.

The invention contemplates the use of bubble trays, perforated pans or any other suitable well known form of fractionating or contact means, not illustrated, within the upper portion of chamber 21 for the purpose of substantially freeing the vapors evolved in this zone of undesirable entrained or dissolved high coke-forming materials and to assist in cleaning up the vapors in chamber 21 provision is made for introducing a suitable cooling oil into the upper portion of this zone through line 31 and valve 32. It is also, of course, within the scope of the invention to employ suitable partial condensing or rough fractionating equipment such as a knock-out drum, heat exchanger or the like in line 33 through which vapors are removed from chamber 21, although this well known expedient is not illustrated in the drawing. By control of the amount of cooling accomplished within chamber 21 or in vapor line 33, the amount of heat supplied to this zone in the conversion products from chamber 17 and/or coil 6 and the pressure employed in chamber 21, the temperature of the relatively clean vapors passing through line 33 may be maintained at a level suitable for accomplishing low temperature catalytic cracking of these vapors. The relatively clean vapors passing through line 33 are directed, in part, through valve 34 in this line to fractionator 13 and, in part, through line 35 and valve 36 to catalytic cracking treatment in the manner subsequently described.

The materials supplied to fractionator 13 which include vapors from chamber 21, any charging stock supplied to this zone and any conversion products of the low temperature catalytic cracking step which may be supplied to this zone 55 in the manner subsequently described, and therein fractionated to form an overhead vaporous stream consisting essentially of materials boiling within the range of the desired final motor gasoline product of the process and gases, and to form reflux condensate consisting essentially of higher boiling fractions. The fractionated vapors are directed from the upper portion of fractionator 13 through line 37 and valve 38 to condensation and cooling in condenser 39 wherefrom the resulting distillate and uncondensed gases are directed through line 40 and valve 41 to collection and separation in receiver 42. Uncondensed gases are released from the receiver through line 43 and valve 44 to storage or elsewhere, as desired. The distillate which comprises the motor gasoline product of the process is directed from receiver 42 through line 45 and valve 46 to storage or to any desired further treatment, not illustrated, such as, for example,

stabilization, chemical treatment to improve its quality, or the like.

When desired, regulated quantities of the distillate collected in receiver 42 may be returned by well known means, not illustrated, to the upper portion of fractionator 13 to serve as a cooling and refluxing medium in this zone.

The total reflux condensate formed in fractionator 13 may be directed from the lower portion of this zone through line 47 and valve 48 to pump 49 and supplied therefrom through line 50, valve 51 and line 9 to thermal cracking treatment in coil 10 or the reflux condensate may be separated in fractionator 13 into relatively light and relatively heavy fractions, the latter being supplied, as described, to coil 10, while selected lighter fractions are removed from a suitable intermediate point in the fractionator through line 52 and directed through valve 53 in this line to pump 54 wherefrom the relatively light reflux condensate is supplied through line 55, valve 56 and line 4 to thermal cracking treatment in coil 6. It is also entirely within the scope of the invention to remove all or any portion of the condensate condensed from the vaporous conversion products in fractionator 13 from the system by well known means, not illustrated.

The catalytic cracking step of the system may employ one or a plurality of catalytic reactors of any desired form and, in the particular case here illustrated, two reactors 59 and 60 are provided. Each of the reactors contains a suitable catalyst which, in active state, is capable of promoting low temperature cracking of the vapors from chamber 21. Each of the reactors is alternately employed as a low temperature catalytic cracking zone and as a zone for effecting reactivation of the catalyst in situ. This reactivation is necessitated by the deposition of heavy carbonaceous materials on the catalyst during the low temperature catalytic cracking reaction and may be accomplished in any well known manner which does not constitute a novel part of the present invention and is, therefore, not illustrated.

While reactor 59 is employed as the low temperature catalytic cracking zone, the vapors from line 35 are directed through line 61 and valve 62 into this zone wherein they contact the catalyst disposed therein and wherein the desired low temperature catalytic cracking reaction is effected, the resulting conversion products being directed from reactor 59 through line 63, valve 64 and line 69 to separating and fractionating column 70.

While reactor 60 is employed as a low temperature catalytic cracking zone, vapors from line 35 are directed thereto through line 65 and valve 66, contact the catalyst disposed within the reactor and are converted in the presence of the catalyst, as in reactor 59. The resulting conversion products are directed through line 67, valve 68 and line 69 to vaporizing and fractionating column 70.

Preferably, since the low temperature catalytic cracking reaction is endothermic, any suitable well known means, not illustrated, is provided for supplying heat to the reactor for maintaining the reactants and the catalyst bed at a suitable reaction temperature and since regeneration of the catalyst is an exothermic reaction involving burning from the catalyst particles of heavy carbonaceous materials deposited thereon during the low temperature catalytic cracking reaction, provision is normally made in any well

known manner, not illustrated for preventing an excessive temperature rise in the catalyst bed during reactivation and thereby avoid damaging of the catalyst.

In case the nature of the vapors subjected to low temperature catalytic cracking treatment, the nature of the catalyst employed for promoting the low temperature catalytic cracking reaction and the conditions of operation employed are such that any substantial quantity of heavy liquid conversion products unsuitable for further cracking treatment in the thermal cracking step of the system are formed, these materials are preferably separated from the lighter vaporous conversion products in the lower portion of column 70 and removed through line 71 and valve 72 to cooling and storage or elsewhere, as desired.

The vaporous conversion products, including materials boiling within the range of gasoline and heavier fractions suitable for further thermal cracking treatment, are fractionated in column 70 to separate therefrom as fractionated vapors a stream consisting essentially of normally gaseous products and gasoline fractions of relatively low end-boiling point as compared with the motor gasoline recovered in receiver 42. The end-boiling point of this stream may be varied to suit requirements, so that the aviation-base gasoline recovered therefrom by condensation will comprise substantially only the relatively light gasoline fractions which are essentially paraffinic and accordingly have a bromine number meeting market requirements for aviation gasoline. This stream is directed from the upper portion of fractionator 70 through line 73 and valve 74 to condensation and cooling in condenser 75, wherefrom the resulting distillate and uncondensed gases are directed through line 76 and valve 77 to collection and separation in receiver 78. The uncondensed gases are released from the receiver through line 79 and valve 80 and the aviation-base gasoline is directed from this zone through line 81 and valve 82 to storage or elsewhere, as desired.

When desired, regulated quantities of the distillate collected in receiver 78 may be returned by well known means, not illustrated, to the upper portion of fractionator 70 to serve as a cooling and refluxing medium in this zone.

Those fractions of the catalytic conversion products supplied to column 70, which boil above the range of the desired aviation-base gasoline and include higher boiling fractions suitable for further thermal cracking treatment, are condensed in this zone as reflux condensate. In the particular case here illustrated, the total reflux condensate is directed from fractionator 70 through line 83 and valve 84 to pump 85 and supplied therefrom through line 86 and valve 87 to fractionator 13, wherein it commingles with the other materials supplied to this zone as previously described and is separated therewith into the desired fractions, as previously explained. Thus, the motor gasoline recovered in receiver 42 will normally contain heavy gasoline fractions produced in the low temperature catalytic cracking step and the cracking stock supplied to coil 6 and/or to coil 10 will include conversion products produced in the low temperature catalytic cracking step which boil above the range of the motor gasoline.

It is, of course, also within the scope of the invention to separately remove the high end-point gasoline fractions as a side stream from fractionator 70 and recover the same as a sep-

arate product of the process or blend them, in regulated quantities, with the motor gasoline resulting from thermal cracking treatment, although well known means for accomplishing this are, for the sake of simplicity, omitted from the drawing. In such cases the heavier fractions of the catalytic conversion products suitable for further thermal cracking treatment may be supplied from fractionator 70 to fractionator 13 or directly from fractionator 70 to cracking coil 6 or to cracking coil 10, as desired.

It is not intended to limit the invention to the use of any specific type of low temperature catalytic cracking catalyst since there are several which are suitable under properly controlled conditions of temperature, pressure and contact time and, apart from the method of operation herein provided, such suitable catalysts are not a novel part of the present invention. Certain naturally occurring or synthetically prepared catalysts comprising alumina and silica, alone or together with other materials, such as oxides of zirconium, thorium or the like or combinations of silica with zirconia and/or thoria or other metal oxides, may be successfully employed. I also contemplate the use of aluminum chloride and other well known cracking catalysts. However, the catalytic material which I have found particularly suitable is silica, prepared from silica gel or the like, comprising a carrier for regulated amounts of alumina or zirconia, or both, and preferably substantially free of alkali metals which fuse at temperatures such as those encountered during reactivation and thereby tend to reduce or destroy the activity of the catalyst.

Preferably, as previously mentioned, a temperature of the order of 650 to 800° F., or thereabouts, is employed in the low temperature catalytic cracking step with relatively low superatmospheric pressures of the order of 30 to 150 pounds, or thereabouts, per square inch and preferably with a space velocity, expressed as the volume of hydrocarbons subjected to catalytic treatment in a given time per unit volume of catalytic material of the order of 0.75 to 2. However, at the present time, the limits of temperature, pressure and contact time, within which "low temperature" catalytic cracking may be successfully accomplished with various types of charging stocks and various catalysts, have not been completely explored and the indications are that temperatures outside the range above given and particularly from 500 to 850° F. or slightly higher and space velocities of from 0.25 to 4 are suitable for some charging stocks and some types of catalyst. I believe, however, that the more limited range of operating conditions above given will generally hold for the treatment of cracked vapors, derived as herein described, with the preferred type of catalyst above mentioned.

The conditions of operation employed in the thermal cracking phase of the system will vary within relatively wide limits, depending upon the type of charging stock employed and the specific form of cracking equipment utilized. In a system such as illustrated and above described, the temperature employed at the outlet of the heavy oil cracking coil may range from 800 to 925° F., preferably with a superatmospheric pressure at this point in the system of from 100 to 500 pounds, or thereabouts, per square inch. The temperature employed at the outlet of the light oil cracking coil is preferably of the order of 900 to 1025° F., with a superatmospheric pressure at this point in the system of from 100 to 1000

75 pounds, or thereabouts, per square inch. The reaction chamber is preferably operated at a superatmospheric pressure of the order of 100 to 500 pounds per square inch and a substantially reduced pressure of the order of 30 to 150 pounds per square inch is preferably employed in the vaporizing and separating chamber, with the succeeding fractionating, condensing and collecting equipment operated at substantially the same or somewhat lower pressure.

As an example of one specific operation of the process as conducted in a system such as illustrated in the drawing, the charging stock is a Mid-Continent topped crude of approximately 25° A. P. I. gravity which is supplied to the fractionator of the system and therein separated, together with the components of the thermal and low temperature catalytic conversion products supplied to this zone which boil above the range of the motor gasoline, into relatively light and relatively heavy reflux condensate fractions.

The heavy reflux condensate is heated in the heavy oil cracking coil to an outlet temperature of approximately 910° F. at a superatmospheric pressure of about 225 pounds per square inch and the resulting conversion products are supplied to the reaction chamber which is operated at substantially the same pressure. The light reflux condensate is heated in the light oil cracking coil to an outlet temperature of approximately 975° F. at a superatmospheric pressure at this point in the system of approximately 350 pounds per square inch and the conversion products from the light oil cracking coil are also supplied to the reaction chamber. Both vaporous and liquid conversion products are removed from the lower portion of the reaction chamber at a temperature of approximately 900° F., cooled to approximately 830° F. and supplied to the vaporizing and separating chamber at a superatmospheric pressure of approximately 110 pounds per square inch. The temperature of the vapors leaving the vaporizing and separating chamber is approximately 770° F. and about 50% of this vaporous stream supplied to the low temperature catalytic cracking step. The vapors enter the catalytic reactor at a temperature of approximately 750° F. A substantially uniform temperature of approximately 750° F. is maintained in the catalytic reaction zone and the resulting conversion products are supplied therefrom to the fractionator of this stage of the system at a superatmospheric pressure of approximately 35 pounds per square inch. An aviation-base gasoline of approximately 300° F. end-boiling point is recovered from the catalytic conversion products and the remainder of the latter, except for a small amount of the residual liquid fractions separated therefrom, is supplied to the fractionator of the thermal cracking step wherefrom motor gasoline having an end-boiling point of approximately 400° F. is recovered.

The above described operation will yield, per barrel of charging stock, approximately 32% of motor gasoline, which includes heavy gasoline fractions produced in the low temperature catalytic cracking step, and approximately 22% of the 300° F. end-point aviation-base gasoline. The residual liquid produced amounts to approximately 38% of the charging stock and the remainder of the latter is chargeable principally to normally gaseous products. The 400° F. end point gasoline has a relatively high content of olefins and aromatics and an octane number of approximately 68. The 300° F. end point gaso-

line has an octane number of about 70, which can be increased to approximately 92 by the addition of 6 cc. of tetraethyl lead, and meets the acid heat test requirements for aviation gasoline. The aviation-base gasoline is high in paraffines, low in olefines and does not contain a sufficient quantity of aromatics to raise its cold test to above market requirements.

I claim as my invention:

1. The process of hydrocarbon oil conversion which comprises thermally cracking an oil under conditions regulated to produce therefrom high yields of gasoline sufficiently high in olefin content to render it unsuitable as aviation gasoline, separating the resulting products into vapors suitable for catalytic cracking and non-vaporous residue under conditions which leave said vapors at sufficient temperature and pressure to initiate catalytic cracking thereof in the presence of a cracking catalyst, separating said vapors into two streams of substantially the same composition, initially contacting one of said streams at no increased temperature or pressure with said cracking catalyst in a zone wherein contact is continued for a time and under temperature and pressure conditions regulated to increase the gasoline content of said stream and materially reduce its olefin content, recovering from the products of the catalytic cracking step a gasoline fraction meeting market specifications for aviation gasoline with respect to boiling range and acid heat test, further separating from the products of the catalytic cracking step a condensate consisting essentially of fractions boiling above the range of said aviation gasoline, commingling said condensate with said other stream of vapors and fractionating the mixture to form reflux condensate and a vaporous stream comprising motor gasoline of higher end boiling point and higher olefin content than said aviation gasoline, condensing and recovering said motor gasoline and supplying reflux condensate formed by said fractionation to the thermal cracking step.

2. The process of hydrocarbon oil conversion which comprises thermally cracking an oil under conditions of elevated temperature and substantial superatmospheric pressure, separating the resulting products into vapors and non-vaporous residue at substantially reduced super-atmospheric pressure and at a temperature of the order of 600-850° F., contacting a regulated quantity of said vapors at substantially the same temperature and no higher pressure with a catalyst which promotes their low temperature catalytic cracking, separating from the resulting products of the catalytic cracking step a fractionated vaporous stream comprising aviation-base gasoline and a higher boiling condensate containing fractions boiling above the range of said aviation-base gasoline, supplying another

portion of the first named vapors and said higher boiling condensate to a separate fractionating step and therein fractionating the mixture to form reflux condensate and a fractionated vaporous stream comprising motor gasoline of higher end boiling point and higher olefin content than said aviation-base gasoline, supplying reflux condensate formed in the last named fractionating step to the thermal cracking operation and separately recovering from said fractionated vaporous streams said aviation-base gasoline and said motor gasoline.

3. The process of hydrocarbon oil conversion which comprises thermally cracking an oil under conditions regulated to produce therefrom high yields of gasoline of relatively high olefin content, separating the resulting products into vapors suitable for catalytic cracking and non-vaporous residue, separating said vapors into at least two streams of substantially the same composition, subjecting one of said streams to catalytic cracking under conditions of temperature, pressure and contact time regulated to increase the total gasoline content of the vapors and materially reduce its olefin content, fractionating the resulting catalytically cracked products to form reflux condensate and to recover therefrom gasoline fractions meeting market specifications for aviation-base gasoline, combining the reflux condensate with another of said streams and separating an automotive gasoline from the mixture, of higher olefin content than said aviation gasoline.

4. The process of hydrocarbon oil conversion which comprises thermally cracking an oil under conditions regulated to produce therefrom high yields of gasoline of relatively high olefin content, separating the resulting products into vapors suitable for catalytic cracking and non-vaporous residue under temperature and pressure conditions at which further cracking of the resulting vapor can be initiated in the presence of a cracking catalyst, separating said vapors into at least two streams of substantially the same composition, subjecting one of said streams to contact with said cracking catalyst under conditions of temperature and pressure approximating those obtaining in the first mentioned separation step and for a contact time regulated to increase the total gasoline content of the vapors and materially reduce its olefin content, fractionating the resulting catalytically cracked products to form reflux condensate and to recover therefrom gasoline fractions meeting market specifications for aviation-base gasoline, combining the reflux condensate with another of said streams and separating an automotive gasoline from the mixture, of higher olefin content than said aviation-base gasoline.
